(57) **CLAIM**

The ornamental design for a modular floor tile set, as shown and described.

DESCRIPTION

FIG. 1 is an enlarged exploded top plan view of a modular floor tile mat showing, respectively, an edge tile, a corner tile and a center tile of my new design;

FIG. 2 is an enlarged exploded bottom plan view thereof, similar to FIG. 1;

FIG. 3 is a perspective view showing a modular floor tile mat of the present invention;

FIG. 4 is an enlarged front plan view of a center tile, the rear plan being a mirror image thereof;

FIG. 5 is an enlarged left side elevational view of a center tile, the right plan view being a mirror image thereof;

FIG. 6 is an enlarged front elevational view of an edge tile thereof;

FIG. 7 is an enlarged rear elevational view of an edge tile thereof;

FIG. 8 is an enlarged right side elevational view of an edge tile thereof;

FIG. 9 is an enlarged left side elevational view of an edge tile thereof;

FIG. 10 is an enlarged side elevational view of an outside edge of a corner tile thereof;

FIG. 11 is an enlarged side elevational view of an edge of a corner tile opposite the edge of FIG. 10;

FIG. 12 is an enlarged view similar to FIG. 10, of the other outside edge of a corner tile thereof; and,

FIG. 13 is an enlarged side elevational view of an inside edge of a corner tile opposite the edge of FIG. 12.
